UNITED STATES PATENT OFFICE.

HJALMAR G. CARLSON, OF WORCESTER, MASSACHUSETTS, ASSIGNOR TO ROCKWOOD SPRINKLER COMPANY OF MASSACHUSETTS, A CORPORATION OF MASSACHUSETTS.

METHOD OF MAKING UNIONS AND THE LIKE.

1,142,303.

Specification of Letters Patent. Patented June 8, 1915.

Application filed December 3, 1914. Serial No. 875,356.

To all whom it may concern:

Be it known that I, HJALMAR G. CARLSON, a citizen of the United States, residing at Worcester, in the county of Worcester and 5 State of Massachusetts, have invented a new and useful Method of Making Unions and the like, of which the following is a specification.

The principal objects of this invention 10 are to provide a simple, inexpensive and practicable method of making pipe unions and other articles of a similar nature having projections at their ends for receiving nuts or other fastening devices and end surfaces 15 adapted to abut against each other; to provide a method of manufacturing such articles from disk-shaped blanks of sheet metal in a minimum number of operations; and more specifically to provide an efficient 20 method of forcing a portion of the sheet metal outwardly in the dies for the purpose of providing a projecting end and a surface at the end of the article suitable for abutting against a complementary surface and 25 forming a tight joint therewith.

Reference is to be had to the accompanying drawings, in which—

Figure 1 is a central longitudinal sectional view of a cup-shaped blank showing one 30 step of the operation; Fig. 2 is a similar view showing the next step; Fig. 3 is a central vertical sectional view of a set of dies for operating on the blank shown in Fig. 2; and Fig. 4 is a longitudinal central sectional 35 view of a complete union comprising a member formed by this method.

In the manufacture of a member of a pipe union or other similar article according to 40 this invention, a circular disk of sheet metal is the original blank which is employed. This disk is first formed by ordinary well-known die pressing operations into the cup-shaped blank *a* indicated in Fig. 1. In this figure the sheet metal blank *f* has been 45 shaped in simple dies to form a cylindrical portion and a flat end *h* with rounded edges. These are formed by a well known die pressing operation from a circular disk of sheet metal. The next operation in forming this 50 member is to punch out the entire end *h* to leave a perforation *j*, as indicated in Fig. 2. This blank is then placed in a set of dies shown in Fig. 3 and comprising a bottom 55 plate 25 having an ejector 26 extending up through it and provided with a central re-

cess 26'. An intermediate die member 27 has a central cylindrical passage therethrough of the same size as the cylindrical blank *f*. A top die member 28 has a concave surface 28' for shaping the top of the blank 60 and is provided with a central removable plunger 29 fixed in position by a screw 30 or the like. The exterior of this plunger has a diameter substantially the same as the internal diameter of the original blank *f*. 65 The upper die 28 with its plunger 29 is brought down on the blank and this results in forcing the metal of the end downwardly. As the bottom of the blank already rests on the top of the head of the ejector 26 and as 70 the plunger 29 is already within the blank so as to support its walls internally, the only result of forcing this metal down is to force it outwardly into the cavity 28', thus enlarging the end of the blank to form the 75 male enlargement *f'* (Fig. 4). It is found in practice that this results in causing the metal to move away from the plunger 29 and to form a circular cavity *f''* surrounding 80 the same which does not weaken the union. This operation having been accomplished, the blank is removed, threaded and machined if necessary, although as a matter of 85 fact it is found that no machining is required especially when brass is used, but when made of iron or steel the convex bearing surface of the enlargement *f'* is finished 85 and the end is usually squared up.

It is to be observed that the member *F*, 90 although formed by a very simple series of operations, is provided with a slight enlargement and square shoulder *f''* for the flange of the nut *G* and is provided with a convex end surface suitable for fitting 95 against the concave end surface of the female member *A*. The dies by which these operations are performed are simple and complete in themselves and they are easily manufactured and operated.

Although I have illustrated the invention 100 as applied to the manufacture of a part of a pipe union, I am aware of the fact that the principles thereof can be carried out in substantially the same way in the manufacture 105 of other articles of a somewhat similar form and that the exact sequence of operations can be changed to some extent without departing from the scope of the invention as expressed in the claims. Therefore, I do 110 not wish to be limited to the manufacture of

this specific article or to the exact order of steps or shape of dies herein shown and described but

What I do claim is:—

5 1. A method of making a member of a pipe union from sheet metal which consists in forming a disk shaped sheet metal blank into a cup-shaped form, perforating the end thereof, forcing a plunger axially into the 10 blank through the perforation, and simultaneously forcing the blank longitudinally in a set of dies and compressing it to form the open end thereof into a cylindrical shape surrounding said plunger and the perforated end into a larger form in contact with the plunger at the bottom and top thereof.

2. A method of making a member of a pipe union from sheet metal which consists in providing a cup-shaped blank having an 20 open end, punching out the entire opposite end thereof, introducing a plunger of the size of said opening into the interior of the cylindrical blank, holding the exterior of the open end of the blank in its original 25 shape and compressing the edge of the op-

posite end around said plunger to increase its diameter, decrease its length, and keep its outer edge in contact with the plunger.

3. A method of making a member of a pipe union which consists in forming a cylindrical blank with both ends open and the corner of one end rounded over, introducing said blank into a set of dies having a passage therein of substantially the same size as the exterior diameter of the blank, placing a plunger of the same external diameter as the interior of the blank into the blank from the rounded end to hold the interior of the blank in shape, and bringing another die of said set against the rounded end of the blank to reduce the length thereof and increase the external diameter around said plunger.

In testimony whereof I have hereunto set my hand, in the presence of two subscribing witnesses.

HJALMAR G. CARLSON.
